CLAIM

The ornamental design for a display screen with icon group and display screen with icon set, as shown and described.

DESCRIPTION

FIG. 1 is a front view of a display screen with icon group showing my/our new design; and,
FIG. 2 is a front view of a display screen with icon set showing an alternative embodiment of my/our new design. The broken lines showing portions of a display screen form no part of the claimed design.

1 Claim, 3 Drawing Sheets
